UNITED STATES PATENT OFFICE.

FRED ADRIAN TRUESDELL, OF YOUNGSTOWN, OHIO.

ROTARY VALVE FOR INTERNAL-COMBUSTION ENGINES.

1,113,512.

Specification of Letters Patent.

Patented Oct. 13, 1914.

Application filed February 7, 1914. Serial No. 817,350.

To all whom it may concern:

Be it known that I, FRED ADRIAN TRUESDELL, citizen of the United States, residing at Youngstown, in the county of Mahoning and State of Ohio, have invented certain new and useful Improvements in Rotary Valves for Internal-Combustion Engines, of which the following is a specification, reference being had to the accompanying drawings.

This invention relates to an improved rotary valve for internal combustion engines and has for its primary object to provide an improved valve of this type more particularly designed for use in connection with the four-cycle type of gas engine whereby the gas is admitted to the combustion chamber of the engine cylinder and the burnt gases exhausted therefrom at the proper times in the reciprocation of the engine piston.

The invention has for a further object to provide improved means for operating a plurality of rotary valves in a multiple cylinder engine directly from the crank shaft thereof.

Another and more specific object of the invention resides in the provision of a rotary valve plate or disk of substantially conical form adapted for engagement with a seating surface formed upon the head of the engine cylinder, and means for automatically supplying a lubricant to the surface of the valve plate between the same and its seat.

The invention has for still another object to generally improve and simplify the construction of valves for internal combustion engines and to increase their reliability and efficiency in operation without adding materially to the cost of manufacture thereof.

With the above and other objects in view as will become apparent as the description proceeds, the invention consists in certain constructions, combinations and arrangements of the parts that I shall hereinafter fully describe and claim.

For a full understanding of the invention, reference is to be had to the following description and accompanying drawing, in which—

Figure 1 is a side elevation of a multiple cylinder internal combustion engine showing the operating means for the rotary valves. Fig. 2 is a vertical section through

the upper end of one of the engine cylinders showing the valve arranged therein. Fig. 2 is a horizontal section showing the arrangement of the valves in an engine with the cylinder cast in pairs. Fig. 4 is a side elevation partly in section of one of the valves removed from the engine cylinder. Fig. 5 is a diagrammatic view illustrating the operation of the valve.

Referring in detail to the drawings, 5 designates the cylinders of an engine which may be of any ordinary or approved construction, and 6 designates the crank shaft thereof. The head of each engine cylinder 70 is internally provided with a valve seat 7.

8 designates my improved valve plate or disk which is of shallow conical form and is provided with an opening or port 9. The valve rod or stem 10 extends centrally through an opening 11 in the cylinder head and upon the same a worm gear 12 is secured. A longitudinally disposed shaft 13 is provided with a series of worms 14, the spiral teeth of alternate worms extending 75 around the shaft in a reverse direction with respect to the remaining worms. These worms 14 are adapted for meshing engagement with the respective worm gears 12 whereby the valve plates or disks are rotated.

As shown in Fig. 2 of the drawings, each pair of engine cylinders is provided with a common intake port 15, to which the intake manifold is connected, and also a common exhaust port 16. The branches 15' and 16' of the intake and exhaust ports respectively, open into the adjacent engine cylinders. The intake ports or openings 15' in the cylinder walls are substantially 90 the same shape and dimensions as the port or opening 9 in the valve disk. This port it will be noted, tapers or is gradually reduced in width from its outer to its inner end, the width thereof being forty-five degrees. The exhaust ports 16' which open through the cylinder walls are however, of slightly greater width than the maximum width of the port in the valve plate, said exhaust ports extending through substantially fifty-four degrees of the circumferential extent of the valve seat.

The several strokes of the engine piston are diagrammatically illustrated in Fig. 5, and the valve disk is shown with its port in registration with the intake port of the cylinder, so that the gas is being admitted to

the combustion chamber of the cylinder. This admission of the gas commences as soon as the port 9 laps over the edge of the intake port 15' and continues through ninety degrees of the rotary movement of the valve.

When the stroke of the piston is reversed to compress the gases the port of the valve is out of registration with the intake port, and said valve during the compression stroke 10 completes another ninety degrees of its rotary movement. In the explosion or power stroke of the piston, the third quarter or ninety degrees of the rotation of the valve is completed and when the piston 15 starts its upward movement on the exhaust stroke, the port 9 of the valve starts its movement across the exhaust port 16 of the engine cylinder, and owing to the additional width of this port, the exhaust will 20 remain open for a greater portion of the rotary movement of the valve than that during which the intake port is open. In other words, the port 9 of the valve plate 25 will lap over the edge of the exhaust port 16' shortly before the piston completes its power stroke or third quarter of 90 degrees and will be in partial or full registration with the exhaust port during the following 30 ninety-nine degrees which completes a single rotation of the valve disk or plate. It is thus apparent that in each two revolutions 35 of the engine crank shaft which is equivalent to the intake, compression, power and exhaust strokes of the engine piston, the valve disk is given a single rotation. The space 40 between the intake and exhaust ports in the head of the engine cylinder is equivalent to the dimensions of the port 9 of the valve disk so that the exhaust 16' will be completely closed before the intake port 15' is 45 opened to admit the gases to the engine cylinder.

The several rotary valve disks are operated through the medium of the power 45 transmission shaft 17 which is provided with a beveled gear 18 on its lower end to mesh with a similar gear 19 on the engine shaft. The upper end of this shaft 17 is also provided with a beveled gear 20 for engagement with the gear 21 on the end of the shaft 13'.

In order to reduce friction to a minimum and eliminate as far as possible wear upon the several valve disks, I provide an improved lubricating means for each of said valves. To this end, the upper surface of the valve disk is provided with a groove 22 which registers with a central longitudinal bore 23 in the valve rod or stem 10. The 55 upper end of this bore communicates with the interior of an oil cup 24 which is suitably mounted upon the upper end of the valve stem. In the groove 22 on the surface of the valve disk, a strip of absorbent material 25 is arranged. It will be readily

understood that the oil or other lubricant in the cup 24 is applied through the bore 23 of the valve stem to the wick 25, which becomes saturated with the oil so that in the rotation of the valve, the oil will be applied to the valve seat 7 and the face of the valve disk.

In an engine provided with my improved valves, the cylinders are preferably arranged in pairs, the cylinder heads being integrally connected and removably secured upon the upper ends of the cylinders by means of the screws or bolts shown at 26. By simply removing these screws, the cylinder heads may be detached so that access may be had to the valves. Owing to the conical form of the valves, the same may be readily ground so that they will properly seat against the cylinder heads and leakage of the compression prevented. My improved lubricating means above referred to maintains a film of oil between the valve and its seat and eliminates waste of the oil.

From the foregoing description taken in connection with the accompanying drawings, it is thought that the construction and manner of operation of the invention will be clearly and fully understood.

My improved rotary valve is extremely simple in its construction and highly efficient and reliable in operation. It will of course be obvious that various other mechanisms for operating the valves may be utilized in putting the invention into practical use, and while the cylinder heads are 95 preferably formed with semicircular combustion chambers, it is obvious that the invention is not limited to this particular construction of the cylinder heads but may be readily applied to the several types of internal combustion engines now in common use. The invention is also susceptible of 100 many other minor modifications in the form, proportion and arrangement of the several parts and I therefore reserve the privilege 110 of resorting to all such legitimate changes as may be fairly embodied within the spirit and scope of the appended claims.

Having thus described the invention, what is claimed is:

1. The combination with an engine having a combustion chamber provided with intake and exhaust ports, and a conical valve seat formed on the wall of said chamber, of a rotary valve mounted in the cylinder head and engaged upon said seat, said valve being provided with an opening to register with the intake and exhaust ports in the rotation of the valve, the surface of the valve which is opposed to said seat being provided with a groove, an absorbent material arranged in said groove, an oil cup carried by the valve to supply a lubricating oil to the absorbent material whereby a film of oil is supplied to the seating face of the 130

cylinder head, and means for rotating the valve.

2. The combination with an engine cylinder provided with a combustion chamber having intake and exhaust ports and a valve seat formed upon the cylinder head, of a rotary valve disk provided with a stem centrally mounted in the cylinder head, said valve disk having an opening adapted to register with the intake and exhaust ports in each rotation of the valve, the surface of the valve disk which is opposed to the valve seat having a groove formed therein,

the valve stem being provided with a central bore communicating with said groove, a strip of absorbent material arranged in said groove, an oil cup mounted upon the valve stem to supply oil to the bore thereof, and means for rotating said valve.

In testimony whereof I hereunto affix my signature in the presence of two witnesses.

FRED ADRIAN TRUESDELL.
